FIG. 2 is a bottom plan view thereof.

The characteristic features of the design reside in the lower portion of the bottle as seen in FIG. 2 and in the area below the horizontal line near the bottom of FIG. 1.

We claim:

The ornamental design for a bottle, as shown and described.
